Letter Patent

The subject referred to in this Letter Patent and making part of the same containing a description in the words of the said Joseph Headwell Derby himself of his machine for cutting combs at a single operation.

The plate or block is usually made of brass, or copper into which are inserted thin plates or bars of hardened steel in such manner as to cut the teeth of the comb out of a single plate or piece of brass in shall at one and the same operation. The operation is performed by placing a piece of brass or steel suitably prepared in the machine and the teeth are then cut by a blow being given theron with a heavy mallet; or the operation may be performed by a press. The piece of brass or steel must be of such dimensions as to form the teeth and the tips or backs of the entire combs, and the teeth of one comb are cut out between the teeth of the other, the tips or backs being left entire and opposite to each other similar to ones placing his fingers between each other, his hands being open and the palm of his hand being considered the tips or backs of the combs, his fingers the teeth, By this method of cutting teeth a saving is made of at least one half of the quantity of stock which would be necessary in the usual method of cutting the teeth with a saw and a great saving is made in the time spent in cutting them.
